[57] CLAIM

The ornamental design for a combined annunciator and telephone jack wall plate and junction box therefor, as shown.

DESCRIPTION

FIG. 1 is a perspective view of a combined annunciator and telephone jack wall plate and junction box therefor showing our new design;

FIG. 2 is a front elevational view thereof;

FIG. 3 is a right side elevational view thereof, the left side being a mirror image;

FIG. 4 is a top plan view thereof, the bottom being a mirror image;

FIG. 5 is a rear elevational view thereof.
